United States Patent Office

Des. 181,657
Patented Dec. 10, 1957

181,657

GOBLET

Raymond T. Kimble, Cambridge, Ohio, assignor to The Cambridge Glass Company, Cambridge, Ohio, a corporation of Ohio

Application April 4, 1956, Serial No. 40,919

Term of patent 3½ years

(Cl. D36—8)

FIG. 1

I claim:

The ornamental design for a goblet, substantially as shown.
